UNITED STATES PATENT OFFICE

ALBERT W. GIVENS, OF MARLBOROUGH, NEW YORK

ENLARGED WEARING SURFACE FOR SPIKE HEELS

Application filed June 30, 1931. Serial No. 547,857.

This invention relates to an article of manufacture in the form of an auxiliary heel for shoes of that kind which may be quickly and easily attached in a temporary manner to the spike heels of ladies' shoes for the purpose of providing a large wearing surface for use on golf courses to prevent damage to the same by the holes which are now made by the spike heels, and thus obviate the necessity of the 10 players having to change their shoes.

The object of the invention is to provide not only a device of this kind but an advertising medium, as the outer surface of the article may be utilized to display an advertisement, 15 which will also help defray the cost of the article so that they may be given away by the owners of the miniature golf course.

Another object of the invention is to provide means whereby the article will fit nearly 20 all sizes of spike heels.

A further object being to provide means whereby the article is reinforced to prevent the end of the spike heel from puncturing through the bottom, and also to stiffen the 25 wearing portion of the article.

With these and other objects in view, my invention consists in certain novel construction and combination of parts as will herein-after be fully described and claimed and 30 illustrated in the accompanying drawing which forms a part thereof and in which like figures of reference refer to corresponding parts in all of the views.

In the drawing:—

35 Figure 1 shows the article as attached to the spike heel of a ladies' shoe.

Figure 2 is a sectional view of the same taken on the line A—A of Figure 3.

40 Figure 3 is a top plan view, taken on the line B—B of Figure 2.

Referring to the drawing:—

The article comprises an auxiliary heel 10 formed of resilient material such as sponge rubber or other suitable material, and having the tapered sides 11 and the large wearing bottom surface 12; the body being formed with a central hole of slightly smaller diameter than the cross sectional size of the spike heel.

50 This hole 13 being for the reception of the

heel 16 of the shoe, which it will grip upon all sides due to its resilient qualities and be firmly retained upon the heel, and yet be quickly put on or removed therefrom.

To add stiffness to the wearing surface or 55 bottom and also to prevent the spike heel from wearing through the bottom 14, the article is provided with a wear plate 15 which is of suitable material such as wood, fiber, metal, etc., and which is incorporated into the 60 manufacture of the article.

It is understood that the article may be of any desired size and shape and of any suitable material, the idea being to convert a spike heel into a large flat heel, such as those 65 on sport shoes, and that the sides of the article may be used to display advertising matter in the form of printing, etc.

Having thus described my invention, what I claim as new and desire to secure by Letters 70 Patent, is—

A detachable enlarged wearing surface for 75 spike heels, comprising a circular tread member integral with a conical heel embracing member having tapered concave sides and a central opening conforming in shape to a cross section of the spike heel, and a metallic disk of greater area than the spike heel secured within said tread between the shoe heel and the wearing surface at an angle thereto. 80

In testimony whereof I affix my signature.

ALBERT W. GIVENS.
